United States Patent Office.

J. S. HUSTON, OF MECHANICSBURG, PENNSYLVANIA.

Letters Patent No. 98,164, dated December 21, 1869.

IMPROVEMENT IN SECURING THE LASHES IN FLY-NETS.

The Schedule referred to in these Letters Patent and making part of the same.

To all whom it may concern:

Be it known that J. S. HUSTON, of Mechanicsburg, in the county of Cumberland, and State of Pennsylvania, have invented new and useful Improvements in Fly-Nets; and I do hereby declare that the following is a full and exact description thereof, reference being had to the accompanying drawings, and to the letters of reference marked thereon.

Figure 1 is a side elevation of a rib, showing the lashes in position.

Figure 2 is a transverse view of a rib through the hole, with lash in and around the same.

The object of this improvement is to obviate the necessity of passing the lash twice through one hole in the rib, as is the case in the ordinary mode of constructing fly-nets, as well as to dispense with the necessity of doubling the lash, in order to form the loop as used heretofore in lashing the ribs together.

To enable others skilled in the art to manufacture and use my invention, I will proceed to describe its construction.

The round rib A is constructed in the usual manner, with holes punched through, at suitable distances apart, to receive the lashes.

The lash is also rounded in the usual manner, of any desirable length or thickness.

The ribs A are lashed together by passing the lash C up through the hole, O, in the rib A. (See fig. 2.) Thence it is passed entirely around the outer periph-

ery of the rib A, from right to left, or *vice versa*, (see figs. 1 and 2,) interlocking the lash C, at the point of juncture, immediately opposite the hole in the rib.

By this means, a much more neat, simple, and economical, as well as a more substantial manner of constructing fly-nets is secured, as any strain on the lashes will not only tend to draw the lashes more securely around the rib, but will serve greatly to strengthen the rib just at the weakest point, by serving as a complete bandage for the same.

I am aware that patents have been granted to other parties by which parallel stitches have been formed in lashing the ribs together; also, various looping-devices, by which the lash is passed twice through one hole, forming a loop or double appearance on the outside of the rib. I make no claim to any such devices; but

What I do claim, and desire to secure by Letters Patent of the United States, is—

The manner of securing the ribs of fly-nets together, by passing the lash singly through the hole in the rib, thence entirely around the rib, from right to left, or *vice versa*, and interlocking the lash, at the point of juncture, immediately opposite the hole in the rib, as shown and described, and for the purpose specified.

J. S. HUSTON.
